UNITED STATES PATENT OFFICE.

EDWY S. PARKER AND THOMAS W. DURANT, OF CHICAGO, ILLINOIS; SAID DURANT
ASSIGNOR TO SAID PARKER.

STARCHING-MACHINE.

1,089,494.

Specification of Letters Patent. Patented Mar. 10, 1914.

Application filed January 24, 1913. Serial No. 743,923.

To all whom it may concern:

Be it known that we, EDWY S. PARKER and THOMAS W. DURANT, citizens of the United States, and residents of the city of 5 Chicago, county of Cook, and State of Illinois, have invented certain new and useful Improvements in Starching - Machines, of which the following is a specification.

Our invention relates to starching machines and the object of this improvement is 10 to provide a machine of this character which will hold work to be starched and protect portions from receiving starch during the process of starching.

15 A further object is to provide a device of this character which is simple in construction and efficient in its operation.

Other objects will appear hereinafter.

The invention consists in the combinations and arrangements of parts hereinafter 20 described and claimed.

The invention will be best understood by reference to the accompanying drawings forming a part of this specification, and in 25 which,

Figure 1 is a top plan view of a machine embodying our invention, Fig. 2 is a longitudinal section of the same, and Fig. 3 is a transverse section of the same.

30 The preferred form of construction, as illustrated in the drawings, comprises a table 1 upon which is secured a block 2 by means of screws 3 or their equivalents. One or more thicknesses of coarser flannel 4 or 35 other similar material is placed on the top surface of block 2 and a piece of finer flannel 5 or other suitable material placed over the absorbent material 4 with its edges 4' extending over the edges of the block 2 and 40 for a short distance on the top of table 1.

A frame 6, composed of wood or other suitable material, is placed around block 2 over the edges of the fabric 5 to securely bind the fabrics or other absorbent materials 4 and 5 to the block 2. In this manner the fabrics or absorbent materials 4 and 5 are removably secured to the block 2. The 45 upper portion of the frame 6 is protected by means of a metallic strip 7, preferably of brass or other suitable metal and secured thereto by means of screws 8, or their equivalents.

40 A lever 9 is inserted through an opening 10 in the table 1 and pivoted as at 11 in a bearing member 12 substantially in the

manner indicated. In said bearing 12 is secured a buffer 13 to limit the swinging of lever 9 in one direction, as will be described later. To the end of lever 9 extending above the table 1 is secured a clamping jaw 14 by 60 means of rivets 15 or their equivalents. The clamping jaw 14 is of a length to extend nearly across the length of the fabric or absorbent material 5. The end of the lever 9 which extends under the table is threaded as at 16 and provided with a counter weight 17 which normally maintains the lever 9 in its dotted line position indicated in Fig. 2.

A second lever 18 is pivoted to the under side of table 1 in a suitable bracket 19 and connected at one end with the lever 9 by means of a slot-and-pin connection 20. The other end of lever 18 is connected to a foot pedal 21 by means of a connecting rod 22 in a manner so that the operator can effect 70 clamping of work on the pad under the clamping jaw 14 and upon releasing the pedal 21 said clamping jaw and levers will take their dotted line positions indicated in Fig. 2.

In operation, absorbent materials 4 and 5, which may be composed of any suitable fabric are placed in position over the block 2 and maintained thereon by means of the frame 6. The portions of work which it is desired to starch are placed on the pad and the clamping jaw 14, by means of the pedal 21 and connecting mechanism, is brought in contact with the work to firmly hold the work on the pad. Said clamping jaw 14 80 also prevents starch from reaching the other portions of the work. By simply freeing the pedal 21, lever 9 will engage stop 13 and the clamping jaw 14 will be brought to inoperative position, by the weight 17, to free 90 the work from the machine. In this device the clamping jaw 14 firmly holds the work in position to be starched and at the same time it serves as a shield to prevent the starch from coming in contact with portions 95 of the articles near the neck bands, cuffs and the like. The absorbent materials 4 and 5 soon become saturated with starch so that all that is necessary is to apply starch to the top side of a cuff, neck band or the like, using a sponge, or other article by which the starch is applied. The cuff, neck band or the like takes starch from the sponge from above and from the absorbent materials 4 and 5 from below until saturated. Suffi- 100 105 110

cient starch also passes from the article after saturation to replenish the starch taken from the fabrics 4 and 5 thereby keeping them in proper condition.

5 While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

10 15 Having described our invention what we claim as new and desire to secure by Letters Patent is:

1. A starching machine comprising a table; a starching pad on said table; a lever 20 extending through and pivoted on said table; a clamping jaw on one end of said lever and coöperating with said pad to hold work; a second lever pivoted on said table and connected to said first mentioned lever

with a slot-and-pin connection therebetween; and a foot pedal operatively connected with said second lever, substantially as described.

2. A starching machine comprising a table; a starching pad on said table; an irregularly shaped lever extending over said starching pad, through and under said table and pivotally connected to the latter; a counter weight adjustably secured on one end of said lever; a work clamping jaw on the other end of said lever; a second lever pivoted to said table and connected to said first lever by a slot and pin connection; and a foot pedal operatively connected with said second lever, substantially as described.

40 In testimony whereof we have signed our names to this specification in the presence of two subscribing witnesses.

EDWY S. PARKER.
THOMAS W. DURANT.
